UNITED STATES PATENT OFFICE.

JOHN WALDER, OF UNION CITY, NEW JERSEY, ASSIGNOR TO C. DE MARTIN, OF UNION CITY, NEW JERSEY.

DESIGN FOR EMBROIDERED LACE.

Application filed October 14, 1927. Serial No. 23,752. Term of patent 7 years.

To all whom it may concern:

Be it known that I, JOHN WALDER, a citizen of the United States, residing at Union City, county of Hudson, and State of New Jersey, have invented a new, original, and ornamental Design for Embroidered Lace, of which the following is a specification, reference being had to the accompanying drawing, forming a part hereof.

The figure of the drawing is a face view showing my new design for embroidered lace.

I claim:
The ornamental design for embroidered lace as shown.

JOHN WALDER.
